UNITED STATES PATENT OFFICE.

FREDERICK C. OVERBURY, OF HILSDALE, NEW JERSEY, ASSIGNOR, BY MESNE ASSIGNMENTS, TO THE FLINTKOTE COMPANY, OF BOSTON, MASSACHUSETTS, A CORPORATION OF MASSACHUSETTS.

ROOFING ELEMENT.

1,295,360.

Specification of Letters Patent. Patented Feb. 25, 1919.

Application filed August 12, 1915. Serial No. 45,207.

To all whom it may concern:

Be it known that I, FREDERICK C. OVERBURY, a citizen of the United States, and a resident of Hillsdale, in the county of Bergen and State of New Jersey, have invented certain new and useful Improvements in Roofing Elements, of which the following is a specification.

This invention has relation to prepared roofing materials, and more particularly those which are laid to present the appearance of tile roofs or other ornamental forms of roofs.

One of the drawbacks to the use of prepared asphalt roofing, even when surfaced with slate or other crushed mineral, is that when laid it is apparently flat and of a monotonous appearance. On the other hand such prepared roofing has many advantages, since it is waterproof and weatherproof, and is durable, comparatively inexpensive and relatively easy to lay.

I have discovered that I am able to break up the monotony of a roof laid with such material, and to give it the appearance of one laid with battens, and, if desired, to cause it to appear as though laid with angular or curved tiles. These effects may be produced by forming the roofing elements with cut-outs or recesses, and, if desired, by employing grit of different colors or shades on the surface of the elements.

Preferably, though not necessarily, the elements consist of shingle strips having along the edge which is to be exposed tabs or projections. In addition to the recesses between these tabs or projections, I provide deeply extending recesses. When the strips are laid in overlapping relation on the roof, these recesses produce an illusory effect of battens, and, with the light coming at certain angles, give the roof the appearance of being formed of curved or angular tiles.

It is difficult, on a mechanical drawing, to reproduce the effect produced by these shingle strips on a roof; however in

Figure 1 I have illustrated a roofing element embodying the invention.

Fig. 2 represents in perspective view a portion of a roofing formed of the strip or element shown in Fig. 1.

Fig. 3 illustrates a similar element formed with strips of differently colored grit to increase the illusion of an undulating or

curved surface such as produced by curved tiles.

Fig. 4 shows a portion of a roof as it appears to a person standing below it.

Figs. 5 and 6 illustrate another form of roofing element embodying the invention.

Fig. 7 shows individual shingles embodying the invention.

While the separate elements may be of any desired length, or may consist of individual shingles, I prefer in most cases to employ shingle strips, which are severed transversely from an elongated sheet of properly prepared roofing felt, and which have on the edges to be exposed spaced tabs or projections. The sheet, from which the elements are formed, is preferably impregnated or saturated with a hydrocarbon water-proofing compound, and, after being coated with pitch or asphalt of a melting point high enough to resist the action of solar heat, it is preferably surfaced with waterproof grit, such as crushed slate or other crushed mineral of the desired color.

In Fig. 1, the shingle strip 10 is cut along its lower edge to form concavely curved pointed tabs or projections 11, through which extend the deep slots, recesses or cut-outs 12.

When such strips are laid in overlapping relation, so that the recesses of one strip register with the recesses of the adjacent strips, as shown in Fig. 2, the roof appears as though covered with curved tiles, and with battens between them. This effect may be heightened by forming the strips with stripes 13 of darker colored grit, as shown in Figs. 3 and 4.

In Fig. 5, the strip has angular tabs 14 through which extend the cut-outs or recesses 15, so as to present the appearance shown in Fig. 6 when laid. A roof so formed presents the appearance of parallel ridges and valleys and with battens in the valleys. This illusion may be heightened by employing strips of darker colored grit.

By varying the configuration of the tabs, many different effects may be produced. The same effect can be secured by cutting the strips thus made into individual shingles as shown in Fig. 7.

Having thus explained the nature of my said invention and described a way of making and using the same, without attempting

to describe all of the ways in which it may be made or all of the modes of its use, what I claim is:

1. A roofing element formed of water-proofed weatherproofed felt and having one or more tabs or projections, and having recesses extending longitudinally of said tabs or projections, the walls of which are adapted to cast shadows and to produce, 10 when said elements are laid in overlapping rows, the effect of raised tiles.
2. A roofing element formed of water-proofed weatherproofed felt, consisting of a strip adapted to be laid with other like 15 strips in overlapping rows, the portion of such strip to be exposed being formed with

tabs or projections having recesses, to produce the illusion of raised tiles.

3. A roofing element formed of water-proofed weatherproofed felt, surfaces with 20 crushed mineral, consisting of a strip adapted to be laid with other like strips in overlapping rows, the portions of such strip to be exposed being formed with tabs or projections having elongated recesses, the 25 crushed mineral on said strip being formed in alternating fields of different color, arranged in predetermined relation to said tabs, to produce the illusion of raised tiles.

In testimony whereof I have affixed my 30 signature.

FREDERICK C. OVERBURY.
